UNITED STATES PATENT OFFICE.

MAX HECHT, OF NEW YORK, N. Y.

DESIGN FOR A BELT ORNAMENT.

SPECIFICATION forming part of Design No. 20,410, dated December 16, 1890.

Application filed November 8, 1890. Serial No. 370,810. Term of patent 3½ years.

To all whom it may concern:

Be it known that I, MAX HECHT, of the city county, and State of New York, have invented a new and original Design for a Belt Ornament, of which the following is a full, clear, and exact description.

Reference is to be had to the accompanying drawings, forming a part of this specification, in which similar letters of reference indicate corresponding parts in both the figures.

Figure 1 is a face view of the belt ornament, showing the design; and Fig. 2 is a cross-section of the same on the lines $\alpha\alpha$ of Fig. 1.

The leading feature of the design consists

of a series of truncated cones A, uniting at or 15 near their bases, and formed in the center with sunken facets B. (Plainly shown in Fig. 2.) In the open space formed by the endless string of truncated cones may be arranged a bar C of cylindrical appearance. 20

I claim—

The design for a belt ornament, substantially as shown and described.

MAX HECHT.
